UNITED STATES PATENT OFFICE.

WILLIAM R. McCOMAS, OF OAKLEY, ASSIGNOR TO THE CRANE & BREED
MANUFACTURING COMPANY, OF CINCINNATI, OHIO.

DESIGN FOR A COFFIN-HANDLE.

SPECIFICATION forming part of Design No. 15,955, dated March 10, 1885.

Application filed December 27, 1884. Term of patent 3½ years.

To all whom it may concern:

Be it known that I, WILLIAM R. McCOMAS, a citizen of the United States, residing at Oakley, in the county of Hamilton and State of Ohio, have produced a new and original design for Handles for Coffins or Burial-Cases; of which the following is a specification, reference being had to the accompanying drawing.

The figure in the drawing represents my newly-produced design.

It consists of a shield-shaped plate on which is the handle proper, said shield having beveled edges ornamented with heraldic designs, showing upon its central portion a raised figure in the form of a pointed ellipse, which elliptical figure in turn displays a raised cir-

cular ornament provided with a cross, the whole of which, as well as the handle proper, being in imitation of beaten or hammered metal, as shown.

Having thus fully described my invention, I claim—

A design for a coffin-handle, consisting of an attaching shield and handle-bar, said shield having beveled edges ornamented with heraldic designs, and bearing a raised elliptical figure, upon which is formed a raised circular design, the whole representing beaten or hammered metal.

Witnesses: WM. R. McCOMAS.
HORACE L. KEENE,
E. W. RECTOR.
